CLAIM

The ornamental design for a lantern, as shown and described.

DESCRIPTION

FIG. 1 is a top, front perspective view of a lantern showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front perspective view of the lantern of FIG. 1, shown in the collapsed orientation;

FIG. 9 is a front elevational view of the lantern of FIG. 1, shown in the collapsed orientation;

FIG. 10 is a rear elevational view of the lantern of FIG. 1, shown in the collapsed orientation;

FIG. 11 is a right side elevational view of the lantern of FIG. 1, shown in the collapsed orientation;

FIG. 12 is a left side elevational view of the lantern of FIG. 1, shown in the collapsed orientation;

FIG. 13 is a top plan view of the lantern of FIG. 1, shown in the collapsed orientation; and,

FIG. 14 is a bottom plan view of the lantern of FIG. 1, shown in the collapsed orientation.

The evenly spaced broken lines shown in the drawings depict portions of the lantern that form no part of the claimed design. The additional dot-dash-dot lines shown in FIGS. 7 and 14 depict the bounds of the claimed design and form no part thereof.

1 Claim, 14 Drawing Sheets
